UNITED STATES PATENT OFFICE.

FREDERICK HEATH, OF BELLINGHAM, WASHINGTON.

STEAM-BOILER PLANT.

Application filed January 26, 1923. Serial No. 615,122.

To all whom it may concern:

Be it known that I, FREDERICK HEATH, a citizen of the United States, and a resident of Bellingham, in the county of Whatcom and State of Washington, have invented certain new and useful Improvements in Steam-Boiler Plants; and I do hereby declare the following to be a full, clear, and exact description of the invention, such as will enable others skilled in the art to which it appertains to make and use the same.

My invention relates to steam-boiler plants which use oil as fuel and the primary object of the invention is to provide novel means whereby the flow of fuel will be automatically cut off if a leak should develop in the oil delivery line. Another object of the invention is to provide means whereby a reduction of pressure in the oil delivery line will cause the flow of steam to the oil pump to be cut off so that the feeding of oil will be arrested until the pressure-reducing cause be overcome. Another object of the invention is to provide an oil-controlling valve which will automatically cut off the flow of oil upon a reduction of pressure in the oil delivery line and which must be manually set to restore working conditions thereby avoiding premature opening of the valve with resultant loss of fuel. Other incidental objects of the invention will appear in the course of the following description, and the invention resides in certain novel features which will be particularly pointed out in the appended claims.

In the accompanying drawings;

Figure 1 is an elevation of a portion of a boiler plant having my present invention embodied therein;

Figure 2 is an enlarged vertical section of the oil control valve;

Figure 3 is a detail section on the line 3—3 of Fig. 2;

Figure 4 is a detail section on the line 4—4 of Fig. 2;

Figure 5 is an enlarged elevation of the plug or piston member of the oil control valve;

Figure 6 is an enlarged longitudinal section of the steam control valve;

Figure 7 is an enlarged section of the working member or piston of the steam control valve.

The boiler furnace 1 may be of any preferred design and may be one of a gang of boilers. It is equipped with oil burners 2

of any approved type and the oil to supply these burners is drawn from a convenient source of supply through a suction pipe 3 by a pump 4. Steam to drive the pump is led thereto through a steam line 5 connected with the steam space of the boiler and a steam control valve 6 is interposed in the steam line. A branch line 7 leads to an arch chamber 8 and a by-pass 9 is provided around the said branch line while a pressure gage 10 is fitted to the branch line. The oil delivery line 11 connects the discharge port of the pump 4 with the burners 2 and a meter 12 is fitted in the said line, a by-pass 13 being provided around the meter. Heaters 14 are connected with the oil delivery pipe and, through a branch 15, with the steam line so that the oil may be heated, if desired, before passing to the burners in order that it may be readily atomized at the burners and consequently burn freely and produce a hot flame. The relation and arrangement of the parts thus far mentioned may be varied to meet conditions and the illustration in Figure 1 is largely conventional.

An oil control valve 16 is fitted in the oil delivery line close to the pump and the discharge side of this valve is in communication, through a tube 17 of small diameter, with the steam control valve 6. The oil control comprises a valve body or casing 18 having an inlet port 19 in its side which is connected with the discharge port or outlet of the pump, and also provided with an outlet port 20 from which the oil delivery line 11 leads and which is preferably diametrically opposite the inlet port. A partition or web 21 is provided within the casing 18 and extends vertically from a point above the outlet port downwardly to a horizontal web or partition 22 which projects inwardly from the side wall of the casing at a point near the bottom of the same, the interior of the casing being thereby divided into a pressure chamber 23 and a passage 24 leading to the outlet port. A port or opening 25 in the web 22 establishes communication between the chamber 23 and the passage 24, and a circular boss 26 is formed on the upper side of the partition or web 22, the upper side of this boss being inclined downwardly toward the web 21 as clearly shown at 27 in Figure 2. Within the chamber 23 and aligned axially with the opening 25 and the boss 26 is a barrel or piston

guide and support 28 having its lower end inclined, as at 29, so as to lie parallel with the surface 27, the barrel being supported fixedly within the casing, as by arms 30 cast integral with the casing and the barrel. A free piston 31 is slidably mounted in the barrel with its lower end adapted to enter the boss 26 and rest upon an internal annular shoulder 32 therein, the piston being provided intermediate its ends with an annular shoulder 33 to engage an annular internal shoulder 34 in the barrel and having a flange or bead 35 at its upper end to rest upon the upper end of the barrel. The piston will thus be firmly supported in its lowest position without jamming and may be readily unseated when the apparatus is to operate. The piston is also constructed with annular grooves 36 to receive piston packing rings 37 so as to have a fluid-tight sliding fit in the barrel. It will be readily understood that the oil entering through the port 19 fills the chamber 23 and surrounds the barrel 28, and it will be readily noted upon reference to Figure 2, that the piston, when in its lowest position, extends across the space between the surfaces 27 and 29 and fills the bore of the boss 26 so that the oil will be held in the pressure chamber. To permit the oil to escape, it is obviously necessary to raise the piston so that at least a portion of the space between the surfaces 27 and 29 will be opened to the bore of the boss 26, and to accomplish this result I provide a plunger or lifting pin 38 which is aligned axially with the piston and is slideable through a gland 39 in the bottom of the valve casing. The lower end of the plunger is pivoted to a lever or handle 40 which is fulcrumed upon a bracket or hanger 41 depending from the valve casing. By swinging the handle upwardly, the plunger is carried against the lower end of the valve piston and caused to raise and unseat the same. As the lower end of the valve piston clears the lowest point of the surface 27, oil will flow into the port 25 and thence through the passage 24 to the oil-delivery line. The volume of the outflowing oil will increase as the piston rises across the escape opening between the surfaces 27 and 29 until the lower end of the piston is within the barrel at which time the maximum flow will be established.

On top of the casing 18 is secured a yoke or open frame 42 in which is mounted a stop rod 43 which is aligned axially with the valve piston and is adjustable toward and from the same through its threaded connection 44 with the top of the frame 42, a handle wheel 45 being provided on the upper end of the rod to facilitate its manipulation. Immediately below the threaded portion of the rod, a pointer disk 46 is carried by the rod to coact with graduations

47 on the frame and enable the operator to accurately adjust the device. If the rod be set in its lowest position, it will bear upon the piston and thereby prevent opening of the valve, and as the rod is raised it will permit the valve to be opened to a greater or less extent so that the volume and pressure of the oil in the delivery line may be very accurately regulated. In the illustrated position of the parts, the valve may have a slight vertical movement but not enough to effect its unseating. A smooth-bored pressure-gage tube 48 is fitted around the stop-rod 43 and a hand wheel 49 on this tube coacts, as a pointer, with the graduations 47 to enable the operator to accurately set the tube. The lower end of the tube has a threaded connection 50 with the bore of a gland 51 fitted in the top of the valve casing, and it will be readily understood that, by reason of this threaded connection, rotation of the tube will cause it to move endwise toward or from the valve piston.

When the valve is open, oil flowing into the chamber 23 will exert pressure upon both ends thereof and the pressure on the upper large end would obviously overbalance the pressure on the lower end and hold the valve in closed position, but the contact of the stop rod with the upper end of the piston reduces the exposed area of the upper end of the piston so that the valve will be balanced. If it be found that the valve tends to close, the exposed area of the upper end of the piston may be further reduced by setting the tube 48 against the piston as will be readily understood.

When the apparatus is operating normally, the pressure of the oil will keep the valve open and the oil will flow to the burners. Should a leak develop in the oil-delivery line or the pressure be reduced from any other cause between the oil control valve and the burners, the valve piston will at once drop to its seat and cut off the further flow of oil. Obviously, the valve will not open automatically but the unseating lever or handle must be raised to effect the opening and, if the handle be raised before the leak is closed, the pressure under the valve will be insufficient to hold it open and it will close as soon as the handle is released. Premature opening of the valve is thus avoided.

The steam control valve comprises a casing 52 having an inlet port 53 in one side and an outlet port 54 in its opposite side, and having a cylindrical chamber 55 between and communicating with the ports. Slidably mounted in the cylinder is a piston 56 having an annular groove 57 intermediate its ends. When the groove registers with the inlet and outlet ports, flow of steam is permitted and the pump will be 120

operated to drive oil to the burners but if the body of the piston at the side of the groove extends across the ports the flow of steam will be cutoff and the pump will stop.

5 The piston is fitted with piston rings 58 to avoid leakage and is carried by a piston rod 59 which plays through a gland 60 in one end of the cylindrical chamber 55, and in the opposite end of said chamber is a conical expansion spring 61 which bears upon the adjacent end of the piston and tends constantly to move the same to the closed or cut-off position. A secondary piston 62 is carried by the piston rod and plays snugly in a secondary cylinder 63 formed in the valve casing in axial alinement with the cylinder 55, and an oil inlet port 64 leads through the wall of the valve casing into said cylinder 63 at the outer side of the piston 62 so that the pressure of the oil will be exerted upon the piston in opposition to the force of the spring 61. The piston rod extends through the valve casing and has its outer end attached to a hand lever 65 fulcrumed upon a post or bracket 66 projecting from the valve casing. Normally the pressure of the oil will overcome the force of the spring 61 and the valve will be held in the position shown in Figure 6, having been set in that position by manual manipulation of the handle 65 when the operation of the apparatus is started. Should there be a reduction of pressure in the oil-delivery line, that reduction will be at once manifested through the by-tube 17, which is connected in the port 64, with a like reduction in the cylinder 63 so that the spring 61 will expand and force the piston to closed position, cutting off the steam and stopping the pump.

40 When normal conditions have been restored, the valve may be reopened and the operation of the apparatus resumed.

From the foregoing descriptions, taken in connection with the accompanying drawings, it will be seen that I have provided a very simple apparatus which will automatically cease to operate upon the development of a leak in the oil-delivery line. The controlling valves are very sensitive and will respond instantly to a very slight reduction of pressure so that the possibility of hot oil being scattered upon the boilers and starting a disastrous fire is rendered negligible. In starting the apparatus, the handle 40 is

swung upward to carry the lifting plunger 55 38 against the piston to unseat the latter which may be set to the desired working pressure by adjusting the rod 43 and tube 48.

Having fully described my invention 60 what I claim as new and desire to secure by Letters-Patent, is:—

1. The combination of an oil burner, a pump, an oil line connecting the pump with the burner whereby oil under pressure will 65 be supplied to the burner, and an oil-control valve interposed in the oil line, said valve closing upon reduction of pressure in the oil line whereby to cut off the further flow of oil.

2. The combination of an oil burner, a pump, an oil line connecting the pump with the burner whereby to supply oil under pressure to the burner, an oil-control valve interposed in the oil line operable to close 75 upon reduction of pressure in the oil line whereby to cut off the flow of oil, and manually operable means to set the valve in open position.

3. The combination of an oil burner, an oil line leading to the burner, means for feeding oil under pressure through the oil line, a valve casing interposed in the oil line, and a valve piston in said casing responsive to pressure in the oil line whereby to close 85 and cut off the flow upon reduction of the pressure.

4. The combination of an oil burner, a pump, an oil line leading from the pump to the burner whereby fuel may be delivered 90 under pressure to the burner, a valve interposed in the oil line to control the flow therethrough and arranged to cut off the flow upon reduction of pressure in the oil line between itself and the burner, a valve controlling the flow of steam to the pump and in communication with the oil line to be normally held open by the pressure in the oil line, and means for closing said valve 95 upon reduction in said pressure.

In testimony whereof, I have signed this specification in the presence of two subscribing witnesses.

FREDERICK HEATH.
